UNITED STATES PATENT OFFICE.

ANTHONY D. BROGAN AND ANDREW M. MALLOCH, OF GLASGOW, COUNTY OF LANARK, SCOTLAND.

DESIGN FOR THE SURFACE ORNAMENTATION OF GLASS.

SPECIFICATION forming part of Design No. 18,705, dated October 30, 1888.

Application filed July 2, 1888. Serial No. 278,864. Term of patent 14 years.

To all whom it may concern:

Be it known that we, ANTHONY DIXON BROGAN and ANDREW MURRAY MALLOCH, citizens of the United Kingdom of Great Britain and Ireland, residing at Firhill, Glasgow, in the county of Lanark, Scotland, have invented and produced a new and original Design for the Surface Ornamentation of Glass, of which the following is a specification, reference being had to the accompanying drawing, forming part thereof.

The design is applied to the surface of glass; and, as represented in the drawing, it consists of a series of diamond lozenge-shaped quadrilateral figures, each of which is bounded by lines 1 *in intaglio*, the said lines crossing each other diagonally throughout the repeat of the pattern. Within the intaglio lines each figure is bounded by marginal lines 2 *in rilievo*, from whence there converge toward the center of

the figure a series of lines, 3, alternately *in intaglio* and *in rilievo*, thus forming a rayonnant figure.

The black lines of the drawing represent the raised lines or ridges and the white portions 25 the grooves or lines *in intaglio* of the design.

We claim—

The design for the surface ornamentation of glass, substantially as herein shown and described.

In witness whereof we have hereunto set our hands and seals this 7th day of May, 1888.

A. D. BROGAN. [L. S.]
A. M. MALLOCH. [L. S.]
